(57) **CLAIM**

The ornamental design for a light emitting diode (LED) pendant lamp, as shown and described.

DESCRIPTION

FIG. 1 is a front elevation view of a light emitting diode (LED) pendant lamp showing the new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a first perspective view thereof; and,

FIG. 8 is a second perspective view thereof.

In FIGS. 1-4, 7, and 8, portions of the design are broken by 2 pairs of break lines. The broken away symbols in the drawings indicate that the appearance of any portion of the article between a pair of break lines forms no part of the claimed design.
